Specification of granted patent number 2,609,665, filed January 26, 1949, and issued September 9, 1952, to Anton Rappi, Eggertsville, N. Y., assignor to Trico Products Corporation, Buffalo, N. Y.

UNITED STATES PATENT OFFICE

2,609,665

ACCESSORY CONTROL SYSTEM

Anton Rappi, Eggertsville, N. Y., assignor to
Trico Products Corporation, Buffalo, N. Y.

Application January 26, 1949, Serial No. 72,964

3 Claims. (Cl. 60—60)

1

This invention relates to certain new and useful improvements in accessory systems for motor vehicles and more especially to the fluid pressure type wherein the accessory motor is supplied with a pressure fluid, either negative or positive, for actuating the same.

Various connections to the power plant have been made to utilize its power in the generation of fluid pressure for the operation of motor vehicle accessories with the much desired flexibility in performance characteristic of the pneumatic type of accessory. These have heretofore required the engine to be operating in order to generate the desired fluid pressure.

The object of the present invention is to provide an improved accessory system in which the fluid pressure may be furnished without the necessity of starting the engine of the vehicle.

A further object is to provide an accessory system which is practical and efficient and one wherein the engine starting system is so combined therewith as to enable reliable accessory performance at all times.

The foregoing and other objects will manifest themselves as this description progresses, reference being made therein to the accompanying drawing wherein:

Fig. 1 is a diagrammatic view showing a practical application of the present invention; and

Fig. 2 is a partial layout of the combined system.

Referring more particularly to the drawing, the numeral 1 designates the starter motor for the vehicle engine 2, the latter having its flywheel gear 3 designed to be engaged by the starter gear 4 upon energization of the solenoid 5. This solenoid is connected into the usual engine starting circuit 6 and, upon becoming operative, actuates the gear shifting lever 7 and at the same time serves in the capacity of a relay to close the switch 8 and the starting motor circuit 9 with the battery 10 which is grounded at 10'. This starter system is conventional and well known.

In accordance with this invention, the starting motor is employed to drive a pump as a source of accessory-operating pressure, either negative or positive, and in a manner to remove the motor, in effect, from the remainder of the starting system. To this end, an accessory control switch 11 is connected by wire 12 to the battery 10 and by a circuit wire 13 to a relay switch 14 which latter is grounded through the motor 1. The relay switch closes the motor field circuit comprising the wires 15 and 16, to

the exclusion of the solenoidal switch 5, 8. The switch 11 may be of any suitable form and is herein illustrated as combined with a valve 19 to constitute the control for the accessory, the latter being shown, by way of example, as a top-lift mechanism having a fluid motor with a chamber 17 and a piston 18.

A fluid line of communication extends from the control valve 19 to each end of the chamber 17, as indicated at 20 and 21. The movable valving member 22 is yieldably held in a neutral position by opposed springs 23 and 24 and may be manually shifted by grasping the knob 25. In either operative position, the valve will connect one side of the accessory motor 17, 18 to the electrically driven rotary pump or compressor 26 by a pipe 27, as the source of superatmospheric pressure, and its opposite side to the intake manifold 28 of the vehicle engine by a pipe 29, as the source of sub-atmospheric pressure. During this valve operation, a finger 30 on the valving member will depress a corresponding one of the switch fingers 31 to close the switch 11. When the springs 23, 24 restore the valving member to its neutral position, the switch will be opened. The valving member 22 is provided with an axial passage 32 having radial ports 33 by which casing ports 20', 21' and 29' are selectively connected and a peripheral channel 34 by which the casing ports 20', 21' and 27' are selectively connected.

For either lifting or lowering the top, the motorist will grasp the knob 25 and shift the valve accordingly thereby closing the auxiliary motor circuit including the starter motor 1 whereupon the latter will become energized to operate the pump and supply a positive pressure which will cooperate with the suction in pneumatically operating the top-lift motor 17, 18. When in its neutral position, the accessory ports 33 will remain in restricted communication with the respective ports 20' and 21' and through the latter in communication with the peripheral channel 34, with the result that when the engine starting system is in use and the pump is generating air currents, the air stream may discharge into the atmosphere by way of the peripheral channel and the axial passage 32 and out through a vent 35.

While a top-lift motor has been illustrated, it is obvious that any other fluid actuated accessory may be substituted or even combined therewith. The starting motor of the vehicle is employed in the secondary capacity as a reliable means for driving the pump so as to

constitute a source of pressure which will enable a consistently uniform performance of the accessory whether it be a top-lifting motor, a window regulator, or other fluid actuated accessory. The pump may be of a suitable design, such as that disclosed in Patent No. 2,520,650.

The foregoing description has been given in detail for clearness only since the inventive principles involved are capable of assuming other physical embodiments without departing from the spirit of the invention and the scope of the appended claims.

What is claimed is:

1. A control system for a fluid actuated accessory of a motor vehicle, comprising, in combination with the starting system of the vehicle including the starter motor and its starting circuit, a pump permanently connected to the starter motor to serve as a source of operating pressure for accessory operation, a control switch connected in circuit with the starter motor, to the exclusion of the engine starting switch, a valve interposed between the pump and an accessory and operable in one position to connect the two for accessory operation and in another position to arrest the accessory, and means operable by the valve in its second position to vent the pump to the atmosphere.

2. A motor vehicle control system comprising, in combination with the electric motor of the engine starting system and with the intake manifold of the engine, a pump constantly operable by the electric motor whenever the motor is operated, a fluid actuated accessory operatively communicating with both the manifold and the pump for actuation by the differential between the pressures of the two, a

valve normally venting the pump to the atmosphere and interrupting both communications and operable to reestablish such communications and to close the vent, and means operable to energize the electric motor to the exclusion of the remainder of the starting system concurrently with the operation of the valve from its normal position.

3. A motor vehicle having a power plant starting system with a starter motor and a starter circuit, a fluid actuated accessory, an air pump permanently connected to the motor to be driven thereby whenever the motor is operated, means for energizing the motor independently of the starting system, and control valve means for the accessory normally venting the pump to the atmosphere when the starting system is in use and operable to connect the pump to the accessory for operation of the latter.
